EX

OR 0 5,877

UNITED STATES PATENT OFFICE.

JEFFERSON J. GRAY, OF BOSTON, MASSACHUSETTS.

DESIGN FOR A PICTURE-FRAME.

Specification forming part of Design No. 5,877, dated May 28, 1872.

Specification describing a Design for "Gre-
cian Picture-Frames," invented by JEFFERSON
J. GRAY, of Boston, in the county of Suffolk
and State of Massachusetts.

The nature of my design is fully represent-
ed by the accompanying photographic illus-
tration, to which reference is made.

A represents the frame proper, and consists
of square pieces of sufficient length for the size
of frame desired. These have a rabbet, into
which may be inserted a gilt inner molding in
the usual manner. The outer frame is joined
at its corners by being halved or notched to-
gether, the ends crossing each other and pro-
jecting beyond the sides and ends a short dis-
tance, in the usual manner. Having thus pre-
pared the frame, I ornament the same by jig-
sawing out ornaments in the form of leaves
B, having openings representing stems *s* cut
through the same. These I glue or nail upon
the four corners of the frame. Upon the side
pieces I affix, in a similar manner, leaves C,
having similar stems cut through them, as in-
dicated by the letter *t*. Upon the top and bot-
tom I affix, in similar manner, leaf or scroll-
shaped pieces D. The frame may be construct-
ed of black walnut, and the leaves or orna-
ments of the same; or the leaves and orna-
ments may be of a lighter-colored wood than

the frame, or vice versa; but I do not consider
this an essential element of the design.

The distinctive character of my design is
found in the leaves and ornaments, which are
of equal thickness in all parts and project from
the face of a smooth frame equally at all points
or edges of the leaves or ornaments, the for-
mer being provided with openings cut through
them, as described and shown.

What I claim as my invention is—

1. A design for a picture-frame, in which the
corner ornaments are composed of leaves B
having openings *s*, substantially in the man-
ner above described.

2. The design of the ornaments C, having
openings *t*, upon the side pieces of the frame
A, substantially in the manner described.

3. The design of the ornaments D upon the
top and bottom of the frame, substantially in
the manner above described.

4. The design of the picture-frame A, with
ornaments B C D having openings *s* and *t*,
substantially in the manner shown and de-
scribed.

JEFFERSON J. GRAY.
